UNITED STATES PATENT OFFICE.

ABRAHAM HUREWITZ, OF NEW YORK, N. Y.

STENCILING DEVICE.

Application filed October 15, 1924. Serial No. 743,301.

This invention has relation to stenciling devices which are particularly designed for the purpose of stenciling packing cases, packages or in any other capacity in which a stenciling device may be used.

The invention contemplates a stenciling device which includes a plurality of individual stencil elements and a frame for interchangeably assembling said elements for use.

One of the outstanding objects of the present invention is to provide a stenciling device of the character set forth which facilitates the interchangeable association of the stenciling elements with the frame member.

The invention furthermore comprehends a stenciling device which is extremely simple in its construction, inexpensive to manufacture and produce and which is highly efficient in its purpose.

With the above recited and other objects in view, the invention resides in the novel construction set forth in the following specification, particularly pointed out in the appended claims and illustrated in the accompanying drawings, it being understood that the right is reserved to embodiments other than those actually illustrated herein, to the full extent indicated by the general meaning of the terms in which the claims are expressed.

In the drawings—

Figure 1 is a plan view of one form of the stenciling device with the stenciling elements associated with the frame;

Fig. 2 is a transverse sectional view therethrough taken approximately on the line indicated at 2—2 in Fig. 1;

Fig. 3 is an enlarged transverse sectional view illustrating the slightly modified form of the invention;

Fig. 4 is a similar view of a further modification of the invention;

Fig. 5 is a fragmentary plan view of a still further modified form of the invention;

Fig. 6 is a sectional view taken approximately on the line 6—6 of Fig. 5;

Fig. 7 is a sectional view taken approximately on the line 7—7 of Fig. 5.

Referring to the drawings by characters of reference and particularly to the form of the invention illustrated in Figs. 1 and 2, 10 designates generally the frame of the stenciling device which is constructed of a single piece of material cut to provide a transverse end member 11 having a plu-

rality of parallel outer and intermediate arms 12 and 13 projecting from one side thereof. The confronting side edges of the outer and intermediate arms 12 and 13 are provided with longitudinal grooves 14 which define guideways for the reception of the offset edges 15 constituting tongues for the stencil elements 16 each of which elements 16 are constructed from a sheet of material 60 having the stenciled letters, numerals or other indicia 17. The stencil elements 16 are adapted to be inserted between the adjacent arms 12 or 13 through the grooves 14 which extend through the free ends of 70 the arms. The offset edges 15 of the stencil elements 16 dispose the bottom faces of the elements 16 in the same plane with the bottom faces of the arms 12 and 13 whereby the complete device may be laid flat upon 75 the surface of the article to be stenciled.

In the modified form of the invention illustrated in Fig. 3 the stencil element supporting frame is made up of two super-imposed sheets of material 18 and 19 so that 80 the arms of the stencil element frame have the lower sheet 19 provided with an intermediate upstanding rib 20 which produces the grooves or guideways 21 for the stenciling devices 16.

In the modified adaptation of the invention illustrated in Figs. 5, 6 and 7 the stenciling device frame is composed of upper and lower sheets of material 26 and 27 and in this instance the arms of the upper sheet 26 90 are provided with upwardly offset side edges 28 which define between said edges 28 and the side edges of the lower sheet 27 the grooves or guideways 29. In this instance it will be also noted that the upper and lower sheets 26 and 27 are connected together by inserting the upstruck tongues 30 of the lower sheet 27 through the slits 31 in the upper sheet 26 as clearly illustrated in Figs. 5 and 6.

I claim—

1. A stenciling device including stencil elements having indicia stenciled therein, and a supporting frame for removably and interchangeably receiving said elements comprising a plurality of parallel arms having grooves in their confronting edges for receiving the edges of the stencil elements, and a transverse connecting member at one end of the same, said frame comprising a plurality of super-imposed connected layers of material.

2. A stenciling device including stencil elements having indicia stenciled therein and a frame for removably and interchangeably receiving said elements to assemble the same, comprising a pair of super-imposed layers of material each including a plurality of spaced parallel arms and a connecting member at one end of the arms, the layer defining one set of arms having rabbed upper corners defining a reduced central rib which together with the side edges of the layer defining the opposite arms produces grooves for receiving the edges of the stencil elements.
- 15 3. A stenciling device including stencil elements having indicia stenciled therein and a supporting frame for removably and interchangeably receiving said elements in assembled relation, comprising upper, lower and intermediate layers of material each 20 having a plurality of spaced parallel arms and a connecting member at one end of the arms, the arms of the intermediate layer being of lesser width than the arms of the upper and lower layers to define grooves at 25 the opposite side edges of the frame arms for receiving the edges of the stencil elements.

ABRAHAM HUREWITZ.
